CONVEYER CONSTRUCTION

John O. Sullivan, Sioux City, Iowa

Application August 28, 1943, Serial No. 500,344

2 Claims. (Cl. 198—195)

1

My invention relates to a conveyer construction.

An object of my invention is to provide a cheaply formed conveyer construction in order to eliminate the necessity of using expensive conveyer belts and the like.

A further object of my invention is to provide a conveyer construction which is made up of a series of spaced lateral slats which slats are interwoven in spaced relation by means of twisted steel wires in a manner somewhat analogous to that structure similar to snow fencing.

A further object of my invention is to provide a driving arrangement in which the drive is applied directly against the slats thereby not requiring extra links, or other appendages.

A further object of my invention is to provide in a modified form, a special arrangement wherein in a plurality of slats are engaged simultaneously by projecting lugs in order to provide an equally divided pressure against each of the slats, and to thereby greatly eliminate wearing of the slats, such effect insuring a longer life to the complete conveyer without undue wear of the individual parts and to also provide a maximum power effect in driving the conveyer.

A further object of my invention, in a modified form is to provide a slat arrangement in which the slats are attached by wires, and in which such slats are adjacent to each other in order to convey sand, gravel, and the like.

With these and other objects in view, my invention consists in the construction, arrangement, and combination of the various parts of my device, whereby the objects contemplated are attained, as hereinafter more fully set forth, pointed out in my claims, and illustrated in the accompanying drawings, in which:

Figure 1 is a sectional view of Figure 4 taken along the lines 1—1 thereof,

Figure 2 is a sectional view of Figure 3 taken along the lines 2—2 thereof,

Figure 3 is a detail of the supporting rollers,

Figure 4 is a plan view of the conveyer,

Figure 5 is a modified form taken along the lines of 5—5 of Figure 6,

Figure 6 is a plan view of Figure 5,

Figure 7 is a modification,

Figure 8 is an enlarged detail,

Figure 9 is a detail of a modified form of the arrangement, taken along the lines 9—9 of Figure 10,

Figure 10 is a bottom view of Figure 9 taken along the lines 10—10 thereof,

Figure 11 is a modified form of slat,

2

Figure 12 is an enlarged section of Figure 11 taken along the lines 12—12 and,

Figure 13 is a further modified form of slat.

My invention contemplates the provision of a conveyer arrangement which is sturdy, and which will provide all of the requirements of a conveyer, whether it be short or long, without necessitating the use of expensive leather, rubber, or other belts the expense of which is excessive. My invention further contemplates the provision of a conveyer wherein a cheaply formed structure is provided through the use of spaced slats which are interwoven between pairs of strong wires or cables which cables are twisted between each respective slat. Such slat structures, through standard production methods can be very cheaply formed and will withstand a great amount of wear and pressure, snow fencing being one of the types of slat structures formed by this method. My invention also provides an efficient driving method wherein the alternate slats are engaged by suitable mechanisms whereby the pressure is applied against the slats directly.

I have used the character 10 to designate a shaft which is driven at the end 11 by means of any suitable power arrangement, the shaft 10 being journaled within suitable posts 12, and attached at 13 to the shaft 10 are a pair of sprockets 14 having the projecting integral lugs 15.

30 The conveyer itself is made up of a series of equally spaced slats 16 which slats are held in spaced relation by the pairs of wires 17 which are twisted together at 18 between slats, this arrangement then providing a continuous conveyer. Between the lugs 15 are provided the recessed spaces 19 the width of which are very slightly greater than the width of the slats 16. The other end of the conveyer system includes a further shaft 20 journaled within posts 21, and 40 which shaft 20 is similarly attached at 22 to identical sprockets 23 having projections 24 the same as the projections 15 and the recessed spaces 25 the same as the spaces 19.

It should be understood that Figures 1 and 4 illustrate the driving, and driven ends of the conveyer, this conveyer being of any required length, with shorter conveyers using smaller slats, and the longer conveyers using stronger and heavier slats, with the slat dimensions also being largely determined by the load the conveyer must carry. In long conveyers it may be necessary to use supports at spaced intervals, and I thereby provide the side brackets 26 which are attached at 27 to the floor or to the ground, etc., and which brackets include bearings 28 in which bearings is

journalized a shaft 29 to which is attached a pair of supporting rollers 30, such rollers being equally spaced laterally to uniformly support the traveling conveyer. Only one roller 30 is shown in Figure 3, although it will be understood that two or more are used, with a similar bracket 26 being positioned at the other side of the conveyer.

It will now be seen that as the shaft 11 is rotated in the direction of the arrow 31 (see Figure 1), the lugs 15 on the sprocket 14 will engage between the slats 16 and move the same, the slats thereby providing the effect of a chain which is driven by the sprocket. As a result the entire conveyer system is moved and the conveyed objects can be placed upon the slats and thereby carried. It should be noted that the pressure of the sprocket lugs against the slats as they move forwardly is applied directly against each slat thereby involving a cheap and yet efficient construction without unnecessary extra chains or other parts.

Figure 5 shows a modified and probably preferred form of the arrangement, especially where greater power is required, and in which the driving shaft is indicated by the character 32 and a further shaft is indicated by the character 33, with such shafts being journalized in the posts or bearings 34. Attached to the shafts 32 and 33 are the pairs of spaced sprockets 35 and 36 including the sprocket teeth 37, and engaging the teeth 37 are a pair of sprocket chains 38 to which are attached at spaced intervals the lugs 39 which lugs are adapted to be received in the spaces between the respective slats 16. The conveyer itself is made up in the same manner as the conveyer described in Figures 1 to 4 inclusive and uses substantially the same construction of slats and wire. The lugs 39 are spaced along the chains 38 so that they engage rather snugly between the slats 16, and the spacing between the shafts 32 and 33 is such so that there will be several lugs 39 engaging against, or forcing several slats at the same time, with the lugs on the top of the arrangement forcing the slats as well as lugs at the bottom thereof. The shaft 32 preferably is the driving shaft in this arrangement, and it will be understood of course that the transverse slats, etc., pass over a driven shaft such as the shaft 29 in Figure 1 having the projections 24, etc.

The above described arrangement has a greater amount of power than the first described arrangement, in that several slats are engaged simultaneously, and also since all of such slats are engaged at one time, there will be correspondingly less wear on each slat, rendering the entire arrangement useful over a long period of time, and allowing the use of wooden slats with a minimum amount of wear. The chains 38 can be provided in different lengths corresponding to the length of the conveyer system, or the weight of the objects carried thereby. The pair of chains 38 also provide a uniform force at either side of the system. The above chain drive system can be placed at any position on the conveyer, and need not necessarily be at the extreme end as shown in Figure 5, it being understood that it can be placed at any position between the ends, with the ends, of course, then passing over further sprockets.

Figure 7 illustrates a further modification in which the individual slats 16 are positioned closely adjacent to each other which slats include the openings at 40 wherein the wires 17 are twisted, and these slats also include cut-out portions at 41 to provide openings which receive the lugs 39 in the modification shown in Figure 5, or the pro-

jections 15 and 24 as shown in Figure 1, etc. These cut-out portions can be formed in the slats 16 by standard production methods so that when they are joined they provide the shapes as shown in Figures 7 and 8. In this latter type of structure, the conveyer can be used for conveying gravel, sand, or other finer materials, and either drive arrangement as shown in Figure 1 or 5 can be used.

Figure 9 illustrates a further modified form of the device in which the slats 42 include the integrally formed extending lugs 43 attached thereto. The lugs can be formed as an integral portion of the slat by forming the entire slat and lug of a suitable plastic, etc., or can be a separate piece firmly attached thereto. In this type of structure the lugs 43 will be received between the pins or rollers 44 of the link chains 38, whereby these pins will then apply the driving force against the individual slats 42, the balance of the chain drive arrangement being as shown in Figure 5.

Figure 13 illustrates a further modification wherein a slat is indicated by the character 45 which slat includes the rectangular openings 46 formed therein. In using this type of slat the conveyer will be driven by means of either the projections 15 of Figure 1, or the lugs 39 of Figure 5 engaging the openings 46 and driving the entire conveyer.

It should be understood that the slats in the above arrangement can be formed of any material consistent with economy, and efficiency.

It will now be seen that I have provided all of the advantages mentioned in the objects of my invention with many other advantages being readily apparent, in a cheaply built structure, which is much cheaper than the expensive belting now commonly employed, and which is efficient in operation.

Some changes may be made in the construction and arrangement of the parts of my invention without departing from the real spirit and purpose of my invention, and it is my intention to cover by my claims any modified forms of structure or use of mechanical equivalents which may be reasonably included within their scope.

I claim as my invention:

1. A conveyer system comprising a plurality of spaced slats, wire members between which said slats are interwoven for supporting and spacing the same, a pair of chain drives, said chain drives being spaced apart laterally with respect to the conveyer, said chain drives including a substantial plurality of lugs attached thereto, said lugs received between said spaced slats and adapted to abut directly against the same for forcible conveying movement thereof, sprockets for driving said chains, means for driving at least one of said sprockets.

2. A conveyer system comprising a plurality of spaced slats, wire members between which said slats are interwoven for supporting and spacing the same, a pair of chain drives, said chain drives being spaced apart laterally with respect to the conveyer, said chain drives including a substantial plurality of lugs attached thereto, said lugs received between said spaced slats and adapted to abut directly against the same for forcible conveying movement thereof, sprockets for driving said chains, means for driving at least one of said sprockets, said chain drives being positioned at one end of said conveyer, said conveyer being continuous, a driven sprocket attached at the other end of said conveyer.

JOHN O. SULLIVAN.
